Henry P. Birkinbine

UNITED STATES PATENT OFFICE.

HENRY P. M. BIRKINBINE, OF PHILADELPHIA, PENNSYLVANIA.

CONSTRUCTION OF GAS-RETORTS.

Specification of Letters Patent No. 12,711, dated April 17, 1855.

To all whom it may concern:

Be it known that I, HENRY P. M. BIRKINBINE, of the city of Philadelphia, in the county of Philadelphia and State of Pennsylvania, have invented a new and useful Improvement in Retorts for Making Gas; and I do hereby declare the following is a full, clear, and exact description of the construction and operation of the same, reference being had to the annexed drawing, making a part of this specification, in which—

Figure 1, is a front elevation. Fig. 2, is a side elevation. Fig. 3, is a section on the line A B. Fig. 4, is a longitudinal section on the line B C.

The ordinary **D** gas retort has cast upon the top of it and forming a part of it an annular space A communicating with the back or closed end of the retort B and extending forward projecting beyond the masonry or setting of the retort where an aperture C for carrying off the gas is provided. The

material from which the gas is to be made is put into the lower compartment B from 25 which the gas is passed through the compartment and is further subjected to the action of heat as it passes forward through the annular space A by this means portions of the material from which the gas is made 30 which passes off in the shape of tar, &c., are further acted upon by the heat and converted into gas.

I do not claim the **D** gas retort nor the passing of gas through a second retort or 35 heater nor a retort with a cellular shell or exterior wall but

What I do claim is—

The **D** gas retort with the annular space above as above described cast with and making a part of it as illustrated by the accompanying drawing.

HENRY P. M. BIRKINBINE.
